UNITED STATES PATENT OFFICE.

FREDERICK J. MAIXNER, OF NEW YORK, N. Y.

DESIGN FOR AN ILLUMINATED-SIGN FRAME.

46,885.

Specification for Design.

Patented Jan. 26, 1915.

Application filed October 7, 1914. Serial No. 865,597. Term of patent 3½ years.

To all whom it may concern:

Be it known that I, FREDERICK J. MAIXNER, a citizen of the United States, residing at New York, in the county and State of New York, have invented a new and original and ornamental Design for Illuminated-Sign Frames, of which the following is a specification, reference being had to the accompanying drawing, forming part thereof.

Figure 1 is a plan view of a frame, showing my new design, and Fig. 2 is a sectional

view of the same, showing more clearly the pebbled front surface A of the frame and its beveled inner and outer edges B and C, respectively.

I claim:

The ornamental design for a frame, as shown.

FREDERICK J. MAIXNER.
